Attorneys

UNITED STATES PATENT OFFICE.

GEORGE S. JACOBS, OF PONTIAC, MICHIGAN.

BRACED ELEMENT.

Application filed April 23, 1923. Serial No. 633,977.

This invention relates to systems of bracing, and is particularly useful in connection with vehicle structures having spaced frame members which are liable to distortion.

More specifically, this invention relates to a system of bracing wherein spaced frame members are connected by a bracing structure engaging the frame members at four separated points approximately in the same plane, the bracing structure comprising means for connecting the separated points of connection by a plurality of arches meeting at points separated from each other on a line substantially perpendicular to the plane of the four points of connection, the connecting members being adapted to withstand stresses either of tension or of compression.

The object of the invention is to provide a simple, strong, durable and inexpensive system of bracing spaced frame members which will hold these frame members rigidly against distortion in different directions.

A further object of the invention is to provide a bracing structure capable of easy modification to suit varying conditions, and readily adaptable for use with spaced frame members used for any purpose where rigidity is desired.

Other and further objects of the invention will appear in connection with the following description, reference being had to the drawing forming a part of the specification, in which—

Figure 1 is a plan view of a preferred embodiment of the invention;

Fig. 2 is a vertical elevation of half of the structure shown in Fig. 1, the central connecting elements being in section on the line II—II of Fig. 1;

Fig. 3 is a plan view of a modified form of the invention, and

Fig. 4 is an end elevation thereof, the side spaced frame members being shown in section.

While the structures illustrated in the accompanying drawing are particularly intended for use with vehicle frames, especially automobile chassis for closed bodies, as a means for preventing distortion, it will be understood that similar bracing structures may advantageously be used with many other structures where it is desired to brace parallel or substantially parallel members to prevent distortion.

In the embodiment shown in Fig. 1, the frame members 1 and 2 may consist of chan-

nel bars, and the brace members 3 may also consist of channel bars split longitudinally of the web for almost their entire length, an end of the web being left solid to form 60 an attaching portion 4 which may be secured to the web 5 of the channel members 1 or 2 as by rivets 6 or other suitable securing means. For many structures, spot welding may conveniently be used. The split portions of the members 2 are bent apart angularly as shown in Fig. 2 to form divergent arms. The free ends of all four members forming a bracing unit, are arranged between the members 1 and 2 so that the diagonally extending arms lie in two intersecting planes, each substantially at right angles to the plane of the four points of connection of the braces with the frame members. Any suitable means may be used to hold the opposed ends of the brace members in fixed relation to each other. As shown in Figs. 1 and 2, the webs and flanges of the brace members are bent adjacent to their free ends, and a connecting plate 7 is rigidly secured 70 to each member of each group of four adjacent ends, the plates lying on opposite sides of the plane passing through the four points of connection of the braces to the members 1 and 2. 75

While the plates 7 are shown as substantially equally distant from the plane passing through the median line of the webs of the frame members 1 and 2, it is evident that either the upper or lower plate may lie nearer to this plane, in which case the divergent arms of the brace members will not be bent at equal angles to the terminal attaching portions 4. In all cases however, the plates 7, or their equivalent means for rigidly uniting the meeting ends of the brace members should lie on opposite sides of the plane passing through the four points of connection of the braces with the frame members. 80

Additional rigidity and strength may be 100 secured by the use of plates or other connecting means such as indicated at 8, the form shown in Fig. 2 consisting of flat metallic sheets cut to fit the tapering space between the flanges of the braces 3, and secured in place by rivets or other suitable means. 105

In the embodiment shown in Figs. 3 and 4, suitable castings or forgings 9 are secured 110 to the frame members 10 and 11, these members 9 having diverging cylindrical terminals 12 adapted to receive tubular brace

members 13 which are joined to the central connecting pieces 14 upon similar cylindrical terminal portions 15. The tubing may be secured to the members 9 or 14 by brazing, welding, or in any other suitable manner as is common in the construction of bicycle frames.

It will be evident to those skilled in the art that many changes may be made in the size, form, proportion, and details of construction of my bracing system without departing from its principles or sacrificing any of its advantages. The system is therefore claimed in any of its embodiments within the full and valid scope of the appended claim.

I claim:—

In motor vehicle construction, a pair of horizontally disposed spaced frame mem-

bers, a bracing structure connected to the frame members at four points approximately in a horizontal plane, the bracing structure having two disconnected points separated from each other on a line approximately perpendicular to the plane of the four points, the bracing structure comprising split channel bars having attaching portions for the frame members and diverging split portions extending towards the separate points on the line approximately perpendicular to the plane of said frame members, a plate connecting the ends of the channel bars above the plane of said frame members, and a plate connecting the ends of the channel bars below the plane of said frame members.

In testimony whereof I affix my signature.

GEORGE S. JACOBS.
